CONTINUOUS HORIZONTAL HOT MOLTEN METAL CASTING APPARATUS

Benjamin Brownstein, Ellwood City, Pa.

Application July 8, 1954, Serial No. 442,098

5 Claims. (Cl. 22—57.3)

This invention relates to an improved method and apparatus for casting and particularly for casting molten metal in substantially horizontal open top molds.

Heretofore, the actual casting of molten metal in such molds has been accompanied with turbulence and agitation. Not only are the dangers of casting relatively large articles increased thereby, but there is appreciable overflow and resulting loss of metal.

Additionally, to cast relatively long articles, such as a channel beam, one practice has been to abut a series of molds endwise and then flow the molten metal in the large recess formed by the molds which extends substantially the combined lengths of the molds. After solidification, the molds are singly stripped from the metal as by being pulled around a wheel while the solid integral cast beam continues on in a straight direction. As the molds are now built, there is an undesirable lifting or "humping" of the long cast beam each time a mold is stripped away.

With my method and apparatus, these objectionable features are entirely eliminated. Instead, casting the molten metal is accomplished smoothly with substantially no agitation or turbulence and with no overflow. In addition, the molds are readily stripped from the cast article without lifting, jarring, or similarly disturbing it.

In my method, I flow a molten metal or other liquid into a mold in a direction substantially parallel to the floor of the mold and simultaneously move the source of the flow and the mold relatively to each other. Preferably, there is a volumetric displacement wherein the volume of the mold traversed by such movement per unit of time is substantially equal to the volume of the molten metal received so that the air in the mold is evenly replaced with the cast molten metal.

The apparatus employed to accomplish this uniform, non-turbulent deposition of molten metal includes a funnel-shaped member having a curved spout to provide substantially a laterally-disposed exit. This member is lowered into the mold and moved relatively thereto. In one embodiment, I link a number of the molds end-to-end. The molds may be butted endwise to form a large recess in which an article may be cast and which extend substantially throughout the combined lengths of the molds. After solidification of the casting, a conveyor joined to the leading mold advances the train of molds. Each mold has a rearwardly extending member and is singly stripped from the cast article without lifting it by being pivoted about the rearwardly extending member as the conveyor moves out of its upper flight.

The accompanying drawings illustrate a presently preferred embodiment wherein:

Figure 1 is a plan view of my casting apparatus with a ladle and crane removed for purposes of illustration;

Figure 2 is a section of Figure 1 on the line II—II;

Figure 3 is a partial plan view of the ladle and crane of Figure 2;

Figure 4 is an offset section of Figure 1 on the line IV—IV with a forward sprocket removed;

2

Figure 5 is a section of Figure 4 on the line V—V; Figure 6 is an offset section of Figure 5 on the line VI—VI and illustrates the sprocket and apron attachment and their operating linkages;

5 Figure 7 is a view similar to Figure 5 and shows the spreader at the rear of the train of molds;

Figure 8 is a view similar to Figure 7 and illustrates the sprocket and apron in a raised position;

Figure 9 is a section of Figure 1 on the line IX—IX;

10 Figures 10 through 14 are transverse mold sections similar to the section shown in Figure 9 and indicate some of the various forms which may be cast with the present apparatus;

Figure 15 is a partial plan view of the molds and supporting frames;

Figure 16 is an offset section of Figure 15 on the line XVI—XVI;

Figure 17 is a section similar to Figure 16 showing the molds in abutting relation;

Figure 18 is a semi-schematic, side elevation of a mold illustrating the stripping action;

Figure 19 is a side elevation of a modified apparatus and illustrates another method of obtaining relative movement between a source of the molten metal and the molds; and

Figure 20 is a diagrammatic electric circuit illustrating how the crane and ladle motors may be synchronized.

Structure

Referring to the drawings, the casting apparatus includes a crane and ladle for the molten metal, generally shown at 10, a spreader and apron at 11 to direct the metal, molds 12 to receive the metal, and a conveyor 13 to carry the molds.

Considering these parts in the order named, a crane 14 (Figures 2 and 3) having an operator's cab 15 conventionally travels rails 16. Forward of the cab, there is a ladle 17 containing molten metal and having trunnion shafts 18 and 19 journaled in bearings 20 which are supported from crane girders 21. A direct-current, adjustable speed motor 22 rotates the shaft 18 through a gear reducer 23 and coupling 24. Motor 22 is connected, for example, in series with a direct-current, adjustable speed motor 22a (Figure 20) which propels the crane in a conventional manner. In this way, one motor does not operate without the other. An adjustable gauge 25 may be placed at a selected pivoted position with respect to its support arms 26 which also are pivotally secured to the sides of the ladle 17. By this arrangement, the flow from the ladle can be restricted as desired by the gauge 25. A funnel 27 receives the metal from the ladle and has a dial 28 to indicate to the operator in the cab 15 if the ladle is being turned at a proper rate. The indicator dial 28 is electrically connected to the operating drive of the ladle 17 and is controlled and operated with the ladle in a conventional manner.

A spreader 29 (Figures 2, 4, 5, and 6) receives the molten metal from the funnel 27 and conducts it directly into the molds 12. The spreader is also funnel-shaped and has a spout of substantially rectangular cross-section which curves as shown to provide a laterally-disposed exit consisting of an upper lip 30 and a lower lip 31. The exit extends across the width of a mold. When the molds comprise a plurality of longitudinally disposed recesses as shown in Figure 9, the bottom lip 31 has a configuration conforming therewith so that the spout may assume at least a very close relation with the floor of the mold. Partitions 32 in the throat of the spout aid in subdividing the flow of molten metal into the desired recesses.

70 An apron 33 is stationed at the level of the upper lip 30 and preferably in contact therewith. To this end, lip 30 and the apron preferably have beveled edges. Crane

girders support the spreader and apron. Plates 34 project downwardly from such girders and carry a shaft 35 which is rotated by a reversible motor 36 through a gear reducer 37 and coupling 38. Outside of each plate 34, shaft 35 has a fixed lever 39. A link 40 connects each lever 39 to a lever 41 fixed to a stub shaft 42 also journaled in the plates 34. An arm 43 fixed to each of the stub shafts 42 is pivotally joined to a side of the spreader 29. Additional arms 44, positioned above the arms 43, pivotally connect at each end to the plates 34 and the sides of the spreader 29 and maintain the spreader in a vertical position when it is raised and lowered. The apron 33 is supported by plates 45 to each of which a bell crank lever 46 is pivotally joined. One leg 47 of each lever pivotally connects to arms 48 and 49 which similarly engage upstanding lugs 50 on the apron. A chain 51 joins the other leg 52 of each of the bell crank levers to a lever 53 fixed to the shaft 35. A stop 54 limits the lowering of the apron. The ladle 17, funnel 27, adjustable gauge 25, spreader 29, and apron 33 may all comprise metal frames having a liner 55 of molded asbestos, fire clay, carbon, or the like to contact the molten metal.

The molds 12 may be composed of cast iron, molded asbestos, molded carbon, or the like. Each mold (Figures 1 and 9 through 17) communicates with adjacent molds so that a single, integral article may be cast which extends substantially the combined lengths of the molds. Accordingly, molds intermediate the end molds usually have no end walls at all. The train of molds may be adapted to cast a variety of elongated articles by providing suitable registering recesses. Thus, substantially rectangular or square beams may be cast with the mold shown in Figure 9, or a single flat plate may be cast with the mold of Figure 10, this mold construction being used in Figure 15 to facilitate illustration of the area below the mold floor. Other modifications include angle beams as shown in Figure 11; half round beams, Figure 12; triangular beams, Figure 13; and channel beams, Figure 14.

Each mold, regardless of internal structure, has laterally expanding flanges 56 and 57, transverse end ribs 58 and 59, and a longitudinal rib 60 joining the end ribs. At the center of the longitudinal rib there is an anchoring lug 61. A frame 62 carries each mold. Each frame includes a longitudinal slot 63 to receive the anchoring lug 61 which thereby positively centers each mold over each frame and yet allows the mold to expand or contract laterally as operating conditions require. Each frame also has upstanding side flanges 64 and 65, and slight recesses 66 adjacent the side flanges in which a strip 67 of asbestos insulating board fits. The flanges 56 and 57 of the mold rest on the insulating board and are held in place with freedom for the mold to expand laterally by gibbs attached to the frame flanges 64 and 65. A stationary gib 68 bears down against flange 56 and is fixed by cap screws 69 to flange 64 from which it is insulated by the asbestos strip 70. Gib 71 is L-shaped and has a key 72 on the longer leg to engage a keyway in flange 57. Cap screws 73 pass through slotted holes 74 in the gib 71 and through insulation 75 to hold the gib to the flange 65. The positions of the cap screws 73 in the slotted holes 74 and therefore the position of the mold 12 as well is determined by adjusting screws 76 which pass through threaded holes in the shorter leg of gib 71 and bear against the side of the frame 62. In this manner, there is an accurate control of the alignment of the molds. The underside of each frame includes transverse ribs 77 and 78 adjacent each end, each of which has a downwardly extending guiding lug 79 at its center. Guiding walls 80 engage the lugs 79 and thereby maintain the frames and molds in a desired longitudinal alignment.

The frames are carried by rollers which are uniquely spaced to aid in stripping the molds from the solidified cast article as hereinafter described. Each frame has rearwardly extending side arms 81 on which rear rollers

82 are mounted. Front rollers 83 are spaced from the actual front of each frame to accommodate the rearwardly extending arm of a preceding mold. Each rear wheel of a frame which precedes another frame is connected to the front rollers of the succeeding frame by means allowing relative movement therebetween. Thus, link 83a having a forked end and link 84 which pivotally engages the legs of the fork both have slotted holes 85 to engage their respective axles 86 and 87 on which the rollers are mounted.

A conveyor is used to support the train of molds below the spreader 29 and also to strip the molds from the cast article and then return them to their former positions. Holding means is also provided to maintain the molds in abutting relation at the time of casting the molten metal. The conveyor (Figures 1, 2, 4, and 15) includes spaced-apart continuous link chains 88 and 89 which travel around forward sprockets 90 and rearward sprockets 91. The sprockets are mounted respectively on axles 92 and 93. Axle 92 is driven by a reversible motor 94 through a gear reducer 95 and coupling 96. The axles, sprockets, and accessory equipment are supported by a series of posts 97 which are reinforced by side beams 98 and transverse beams 99. The transverse beams, in turn, carry a support 100 for the guiding walls 80, tracks 101 on which the rollers 82 and 83 ride, and plates 102 over which the link chains slide. The lower flight of the conveyor is similarly supported. Tracks 101a carry the rollers, and plates 102a carry the chains. If desired, the tracks 101 and plates 102 may slope downwardly somewhat toward the forward sprockets 90 to overcome the sluggish flow of some molten metals. The leading mold frame is connected to the chains. A cross bar 103 fastened to chains 88 and 89 has interconnecting links 104 extending to an axle 105 of the leading frame. As shown, the links are connected by pins 106 engaging slotted holes 107 to provide relative movement between the cross bar 103 and axle 105.

Behind the forward sprockets 90 there is a fluid-actuated cylinder 108 trunnion mounted on the side of a post 97. The piston 109 of the cylinder operates a lever 110 which pivots a cross arm 111. This cross arm bridges the molds and is journaled at opposite sides in bearings 112. The center portion of the cross arm 111 is offset so that the cross arm does not interfere with the travel of the molds when in a raised position. A base 113 rearwardly of the conveyor (Figures 1, 2, and 7) supports two fluid-actuated cylinders 114 and 115 on a level with the molds 12. The pistons 116 and 117 of the cylinders are joined by a rear cross head 118 and a forward cross head 119 which engages the last mold in the train. Cross head 119 has legs 120 on which rollers 121 are journaled. Tracks 122 on the base 113 support the rollers and cross head 119 when the pistons are retracted. Tracks 122a support the rollers 121 and cross head 119 when the pistons are thrust forwardly.

Figure 19 illustrates a modification. Some mill layouts may not have sufficient room to permit a crane and ladle and auxiliary equipment to move along a horizontal runway due to the location of converters, open hearth furnaces, pouring platforms, and the like. Relative movement between the source of the molten metal and the molds can still be obtained by placing the ladle 17a, funnel 27a, and spreader 29a in a stationary position and mounting the conveyor, molds, fluid-operated cylinders, and accessory equipment, which are otherwise the same, on a platform 123 by means of standards 124. Trucks 125 and 126 transport the platform along rails 127. Truck 125 may be conventionally driven by a motor 128 operating the meshing gears 129 and 130.

Operation

In operation, the molds are brought to the top flight of the conveyor and cylinder 108 operated to lower the cross arm 111 from the position shown by the dotted

lines 131 in Figure 5 to a position in front of the leading mold. Cylinders 114 and 115 are then operated to bring the cross head 119 against the last mold in the train. This action pushes the leading mold against the cross arm 111 and rams the succeeding molds into the abutting relation illustrated in Figure 17. The molds are treated with hot tar, asbestos cement, or other commercial mold treating product, particularly along their abutting edges, and are then ready for the pouring.

Ladle 17 is filled with metal preferably equal in volume to the combined volumes of the molds as by weighing the charge from a main ladle in a conventional manner. The operator moves the ladle 17, funnel 27, and spreader 29 over the molds. Motor 36 is energized to rotate shaft 35 so as to slacken the chains 51. This permits the bell crank levers 46 to lower the apron 33 until leg 52 hits the stop 54 when the apron is approximately at the level of the molds. Immediately after the apron starts to descend, levers 39 and 41 and links 40 and 43 lower the spreader so that the bottom lip 31 of the curved spout is at least immediately adjacent the floor of the leading mold when motor 36 stops. If the mold has recesses, the lower lip 31 conforms thereto so that the spreader and molds fit together as shown in Figures 4 and 5. In some cases, particularly where warpage is not apt to occur, the spreader may actually contact the mold.

At this time, the adjustable gauge 25 may be positioned to provide a slot of desired width between the pouring lip of the ladle 17 and the gauge. From his cab 15, the operator jointly energizes motors 22 and 22a. As shown in Figure 20, these motors may have their leads 135 and 136, respectively, connected in series through a main operating controller switch 137 having a manually-operated handle 138 and input leads 139. These motors are timed so that motor 22 continuously turns ladle 17 to maintain a level of molten metal over the slotted opening between the gauge 25 and ladle 17 and to empty the ladle at the time motor 22a brings the crane to the end of the mold train as shown in Figure 7. One way to do this is to incorporate conventional adjustable motor speed controllers 140 and 141, such as rheostats, in the leads 135 and 136, respectively. The correct setting may be determined for a given casting operation and usually is constant for that operation. While pouring from the ladle, the operator watches the indicator 28 and may, if desired, regulate the speed of motors 22 and 22a accordingly. The pouring operations, particularly at the first and last molds, are controlled by limit switches in a conventional manner. The switches, therefore, are not shown. As the spreader is moved along the molds, the latter receive the molten metal. When the mold has a number of recesses, the partitions and conforming shape of the spreader direct the molten metal into the proper channels and away from the tops of the intervening walls. Particularly when the substantially uniform flow of metal, as controlled by the setting of gauge 25 and the synchronized action of the motors 22 and 22a, substantially equals the volume of mold traversed by the spreader per unit of time, there is what I term a volumetric displacement, and the casting step is especially quiescent and free of turbulence and overflow. The air in the molds is evenly displaced by the inflowing metal. During this time, the apron 33 smooths the molten metal as it is discharged from the spreader and confines the upper level of the molten metal for at least a portion of its horizontal travel. The apron also counteracts any tendency of the molten metal to overflow or spill over the sides of a mold. Otherwise, when hot molten metal contacts the relatively cold metal of the apparatus, the molten metal solidifies and seriously interferes with the operation of the various machine parts.

If the embodiment of Figure 19 is used, truck 125 moves the conveyor and accessory parts in the direction of arrow 132 to obtain the same casting operation as described. Motor 128 can be similarly timed with motor 22 to provide substantially equal volume displacement of

air in the molds with the volume of metal received. In either case, when the spreader reaches the end of the train of molds, motor 36 is again operated but in a reverse direction. The spreader 29 is accordingly raised first by the described linkage. Shortly after the spreader begins to rise, the apron 33 also rises so that these parts are above the molds in a noninterfering position, as shown in Figure 8. The longitudinal expansion of the mold and mold frames takes place toward the fluid-actuated cylinders 114 and 115. The cross head 119 can be moved backwardly as operating conditions require. The described lateral movement of the molds in the frames accommodates expansion in that direction.

After the casting has solidified, cylinder 108 is operated to lift the cross arm 111 out of the path of travel of the molds. Motor 94 is started and by the chains 88 and 89 and cross arm 103 advances the molds 12 toward the right as viewed in Figure 2. This causes the molds to separate, as shown in Figure 16, when the axles 86 and 87 are pulled to the farthest ends of the slotted holes in links 83a and 84. The motion of the mold travel is guided by the guiding lugs 79 and walls 80. This motion also releases the casting from the gripping action of the molds. As the molds move around the forward sprockets 90, there is an accelerated front end movement which frees the bottom of any mold still adhering to a casting. A roller table 133 receives the elongated casting and carries it away from the molds. It is especially emphasized that upon passing around the forward sprockets, each mold and mold frame are pivoted about the rear rollers 82 which are carried by the side arms 81 extending past the end of the mold frame. Accordingly, there is a movement away from the casting at all points along the mold, and each mold is stripped away from the casting as shown in Figure 18 without in any way lifting, jarring, or similarly disturbing it. The position of the molds in the lower flight of the conveyor is shown by dotted lines. Subsequently, motor 94 is reversed and the molds 12 are backed into their original positions in the top flight of the conveyor. Thereafter, the operation as described is repeated.

While the foregoing disclosure describes a presently preferred embodiment and modifications thereof, it is understood that the invention may be practiced in still other forms within the scope of the following claims.

I claim:

1. Casting apparatus including a conveyor, a plurality of molds positioned end-to-end and adapted to be advanced longitudinally by the conveyor, each mold communicating with adjacent molds whereby a single, integral article may be cast which extends substantially the combined lengths of the molds, means to center the molds for their longitudinal travel, rearwardly extending side arms on each mold, a rear roller on each side arm, a front roller on each side of each mold but spaced from the front thereof to accommodate the rearwardly extending arm of a preceding mold, at least one side arm on each mold having a trailing link connected thereto and disposed adjacent the corresponding rear roller thereof and adjacent a front roller of the succeeding mold to link the molds together, said link having slotted holes to allow relative movement between said molds, means for pressing the molds together to eliminate the slack from the slotted holes in the links and hold the molds in fixed abutting contact to receive a molten charge, and means to move the conveyor whereby as the molds leave the upper flight of the conveyor they pivot about the rear rollers and strip away from the solidified charge without lifting it at any point.

2. Casting apparatus including a plurality of molds positioned end-to-end and communicating with one another whereby a single, integral article may be cast which extends substantially the combined lengths of the molds, each mold having rearwardly extending side arms, a link connecting each arm of a mold preceding another mold

to the succeeding mold; a rear roller on each side arm, a front roller on each side of each mold but spaced from the front thereof to accommodate the rearwardly extending arm of a preceding mold, said links having slotted holes to allow relative movement between said connected molds; a connector joining the leading mold to the chains whereby the molds are advanced longitudinally, runways substantially paralleling the chains to carry the rollers, a guide to center the molds for their longitudinal travel, means to hold the molds in fixed abutting contact to receive a molten charge including a stop adapted to engage the leading mold, means to engage the rearmost mold and force the molds into endwise contact, and means to move the conveyor chains whereby as the molds leave the upper flight they pivot about the rear rollers and strip away from the solidified charge without lifting it at any point.

3. Casting apparatus including a plurality of molds positioned end-to-end and adapted for longitudinal travel, each mold communicating with adjacent molds whereby a single article may be cast which extends substantially the combined lengths of the molds, a rearwardly extending arm on each mold, a link connecting each arm of a mold preceding another mold to the succeeding mold and adapted to allow relative movement therebetween, means to hold the molds in abutting relation to receive a charge, means to move the molds longitudinally, and means to pivot each mold about the arm whereby the molds may be stripped from the charge after solidification without lifting it at any point, and apparatus for introducing a liquid into the molds with a minimum of turbulence and no overflow including a funnel to conduct the liquid, means to insert and withdraw the funnel with respect to the molds, said funnel having a curved exit spout extending substantially across an internal dimension of the mold and directed substantially toward a wall of the mold, an apron supported adjacent the upper lip of the curved spout on the side of the funnel toward which the spout curves to smooth the liquid discharged from the funnel, and means to move the funnel and apron relatively with respect to the molds.

4. Casting apparatus including a conveyor, a plurality of molds positioned end-to-end and adapted to be advanced longitudinally by the conveyor, each mold communicating with adjacent molds whereby a single, integral article may be cast which extends substantially the combined lengths of the molds, means to center the molds for their longitudinal travel, rearwardly extending side arms on each mold, a rear roller on each side arm, a link connecting each arm of a mold preceding another mold to the succeeding mold, a front roller on each side of each mold but spaced from the front thereof to accommodate the rearwardly extending arm of a preceding mold, said links having slotted holes and cooperating with said rollers to allow relative movement between said connected molds, means to hold the molds in fixed abutting contact to receive a molten charge, and means to move the conveyor whereby as the molds leave the upper flight of the conveyor they pivot about the rear rollers and strip away from the solidified charge without lifting it at any point, and a spreader for casting the molten charge into the molds with a minimum of turbulence and agitation and no overflow including a funnel having a curved spout to provide substantially a laterally-disposed exit, said spout having a configuration to conform with that of the floor of the molds, means to lower the funnel into the mold whereby the laterally-disposed exit is substantially directed

toward a wall of a mold and said conforming configurations are brought at least into adjacent relation, and means to move the funnel and molds relatively to each other while the funnel is in the mold.

5. Casting apparatus including a plurality of molds positioned end-to-end having a plurality of registering, longitudinally-disposed recesses in each of which a single, integral article may be cast which extends substantially the combined lengths of the molds, each mold having rearwardly extending side arms, a link connecting each arm of a mold preceding another mold to the succeeding mold; a rear roller on each side arm, a front roller on each side of each mold but spaced from the front thereof to accommodate the rearwardly extending arm of a preceding mold, said links having slotted holes to allow relative movement between said connected molds, a conveyor chain on each side of the molds, a connector joining the leading mold to the chains whereby the molds are advanced longitudinally, runways substantially paralleling the chains to carry the rollers, a guide to center the molds for their longitudinal travel, means to hold the molds in fixed abutting contact to receive a molten charge including a stop adapted to engage the leading mold, and means to engage the rearmost mold and force the molds into endwise contact, and means to move the conveyor chains whereby as the molds leave the upper flight of the conveyor they pivot about the rear rollers and strip away from the solidified charge without lifting it at any point, a spreader for directing the molten charge into the recesses including a funnel having a spout of substantially rectangular cross-section, said spout having a curved end to provide a substantially laterally-disposed exit, said exit being adapted to extend across the width of the molds, the bottom lip of said curved end having a longitudinal configuration conforming with the floor of the molds, an apron supported adjacent the upper lip of the curved end on the side of the funnel toward which the end curves to smooth the liquid discharged from the funnel and confine its upper level, means to lower the funnel and apron into the mold to station the upper lip of the curved end at substantially the height of the liquid level in the molds and to station the lower lip in at least adjacent relation with the conforming configuration of a mold floor whereby the laterally-disposed exit is directed toward a wall of a mold and the liquid is directed only into the recesses, means to move the funnel and apron relatively to the molds in a direction opposite to that in which the end of the funnel curves and at a rate whereby the volume of the molds traversed by the movement is substantially equal to the volume of the charge received, and means to raise the funnel and apron from the mold.
